UNITED STATES PATENT OFFICE.

JAY G. WAIT, OF STURGIS, MICHIGAN.

FENCE-POST.

SPECIFICATION forming part of Letters Patent No. 732,242, dated June 30, 1903.

Application filed October 6, 1902. Serial No. 126,215. (No model.)

To all whom it may concern:

Be it known that I, JAY G. WAIT, a citizen of the United States, residing at the city of Sturgis, in the county of St. Joseph and State 5 of Michigan, have invented certain new and useful Improvements in Fence-Posts, of which the following is a specification.

This invention relates to improvements in artificial-stone or concrete fence-posts and the 10 like.

It relates particularly to an improved combination artificial-stone or concrete and metal post.

The objects of this invention are, first, to 15 provide a combination artificial-stone or concrete and metal fence-post which may be comparatively small and light and at the same time be strong and durable; second, to provide an artificial-stone or concrete and metal 20 fence-post to which any style of wire fencing may be secured without any special adaptation; third, to provide an improved stone or concrete and metal fence-post to which the fence 25 may be readily attached or removed.

Further objects will definitely appear in the 30 detailed description to follow.

I accomplish the objects of my invention by the devices and means described in the following specification.

The invention is clearly defined, and pointed 35 out in the claims.

A structure embodying the features of my invention is fully illustrated in the accompanying drawings, forming a part of this specification, in which—

Figure 1 is an elevation view of a fence-post embodying the features of my invention. Fig. 2 is a detail longitudinal view taken on a line corresponding to line 2 2 of Fig. 3. 40 Fig. 3 is a detail cross-sectional view taken on a line corresponding to line 3 3 of Fig. 2. Fig. 4 is a detail cross-sectional view taken on a line corresponding to line 4 4 of Fig. 2. Fig. 5 is a detail perspective view of the core 45 and attaching plate B.

In the drawings the sectional views are taken looking in the direction of the little arrows at the ends of the section-lines, and similar letters of reference refer to similar 50 parts throughout the several views.

Referring to the drawings, the body portion A of the post is formed of suitable artificial-

stone or concrete composition, preferably a composition of Portland cement. The core-plate B, formed of sheet metal, is embedded 55 in the body portion A and forms a strengthening and binding means therefor. The rear edge of the core-plate B is formed into a hook B''. This binding action is increased by striking up portions of the metal, as at c, to form 60 tongue-like lateral extensions. The edge of the core-plate B projects beyond the concrete and is formed into an eye or bead B', which is notched laterally, as at b, to receive the longitudinal strands C of the fence. The 65 strands of the fence are placed in these notches and are all secured in position by inserting a vertical lock-rod e through the eyes B'. The notches b are preferably formed quite close together, so that any style of fence 70 may be secured in position—that is, so that it will accommodate fences in which the distances between the longitudinal strands vary. The longitudinal strands can be placed closer together at the bottom of the fence and at 75 greater distances toward the top, as is illustrated in the drawings. It is apparent that by this means the fence can be quickly secured to or detached from the post. The end of the lock-rod e can be bent or kinked at the 80 top and bottom to prevent its accidental displacement.

The core-plate B preferably extends the full length of the post, as illustrated. It is found entirely practical, however, to extend 85 the same only short distances below the ground-line of the post.

The base portion of the post A' is preferably enlarged, so that the earth will have a greater supporting action, as in my improved 90 core it is entirely practical to form the post comparatively small in cross-section, as the core-plate B firmly binds the body portion together, so that the post is strong and durable and capable of sustaining heavy shocks 95 without injury. This advantage of lightness and strength in artificial-stone and concrete posts is very great, both in the saving of material in construction and the expense in handling or transportation.

I have illustrated and described my improved fence-post in detail in the form preferred by me on account of its economy in manufacture and convenience in use. I am

aware, however, that it is capable of considerable variation in structural details without departing from my invention.

Having thus described my invention, what I claim as new, and desire to secure by Letters Patent, is—

1. In an artificial-stone or concrete fence-post, the combination of a body portion; a core-plate B of sheet metal with projecting tongues c thereon, and having a hook B" formed on its rear edge, and its forward edge turned upon itself to form an eye B' embedded in said body portion so that said eye portion projects beyond the face of the said post; lateral notches in said eye portion adapted to receive the longitudinal strands of a fence in said eye portion; and a lock-rod adapted to be inserted through said eye, for the purpose specified.
2. In an artificial-stone or concrete fence-post, the combination of a body portion; a core-plate B of sheet metal having a hook B" formed on its rear edge, and its forward edge turned upon itself to form an eye B' embedded in said body portion so that said eye portion projects beyond the face of the said post; lateral notches in said eye portion adapted to receive the longitudinal strands of a fence; and a lock-rod adapted to be inserted through said eye, for the purpose specified.
3. In an artificial-stone or concrete fence-post, the combination of a body portion; a core-plate B of sheet metal with projecting tongues c thereon and having its forward edge

turned upon itself to form an eye B', embedded in said body portion so that said eye portion projects beyond the face of the said post; lateral notches in said eye portion adapted to receive the longitudinal strands of a fence; and a lock-rod adapted to be inserted 40 through said eye, for the purpose specified.

4. In an artificial-stone or concrete fence-post, the combination of a body portion; a core-plate B of sheet metal having its forward edge turned upon itself to form an eye 45 B', embedded in said body portion so that said eye portion projects beyond the face of the said post; lateral notches in said eye portion adapted to receive the longitudinal strands of a fence; and a lock-rod adapted to be inserted through said eye, for the purpose specified.

5. In an artificial-stone or concrete fence-post, the combination of a body portion; a core-plate B of sheet metal having its forward edge turned upon itself to form an eye 55 B' and embedded in said body portion so that said eye portion projects beyond the face of said post; lateral notches in said eye portion adapted to receive longitudinal strands of 60 fence, and means for retaining said strands in said notches, for the purpose specified.

In witness whereof I have hereunto set my hand and seal in the presence of two witnesses.

JAY G. WAIT. [L. S.]
